(57) **CLAIM**

The ornamental design for a kneeling bench, as shown and described.

DESCRIPTION

FIG. 1 is a perspective view of the kneeling bench showing my new design, with the slat between the two paddles; FIG. 2 is a front elevation view thereof; FIG. 3 is a back elevation view thereof; FIG. 4 is a right side elevation view thereof; FIG. 5 is a left side elevation view thereof; FIG. 6 is a top plan view thereof; FIG. 7 is a bottom plan view thereof; FIG. 8 is a perspective view of the kneeling bench with the slat in an alternative position between the two paddles; FIG. 9 is a perspective view of the kneeling bench with the slat detached from the two paddles to show aspects of the design that may not be apparent in the other views; and, FIG. 10 is a perspective view of the kneeling bench with the slat detached from the two paddles in an alternative position to show additional aspects of the design that may not be apparent in the other views.
